Primary Examiner — Janice Patyk(74) Attorney, Agent, or Firm — MacMillan, Sobanski & Todd, LLC(57) CLAIM

The ornamental design for a knife block as shown and described.

DESCRIPTION

FIG. 1 is a perspective view of a knife block showing my new design.

FIG. 2 is a front view thereof.

FIG. 3 is a rear view thereof.

FIG. 4 is a left side view thereof, the right side view being a mirror image thereof.

FIG. 5 is a top view thereof; and,

FIG. 6 is a bottom view thereof.

The broken lines in the figures illustrate the portions of the design that form no part of the claimed design.

1 Claim, 4 Drawing Sheets(56)
